UNITED STATES PATENT OFFICE.

JOHN W. ESHELMAN, OF NEW YORK, N. Y.

MACHINE FOR EXTRACTING THREADS FROM WOVEN FABRICS.

1,097,216.

Specification of Letters Patent. Patented May 19, 1914.

Application filed September 4, 1913. Serial No. 788,140.

To all whom it may concern:

Be it known that I, JOHN W. ESHELMAN, a citizen of the United States, and resident of the borough of Brooklyn, in the city and State of New York, have invented a new and useful Improvement in Machines for Extracting Threads from Woven Fabrics, of which the following is a specification.

In machines for extracting threads from woven fabrics, it is extremely desirable that the threads to be extracted should be accurately and surely deflected from the plane of the body of the fabric with the least possible disturbance to the body of the fabric and that such deflected threads should be entirely and rapidly removed. My present invention is directed to the provision of novel means for accomplishing the above advantages.

My invention comprises certain improvements in the construction, form, arrangement and operation of the several coacting parts of a thread extracting machine whereby only the desired threads are deflected from the body portion of the fabric and said deflected threads are acted upon by a rotary thread removing means which is operable to act more than once upon the threads deflected by each action of the thread deflecting means, so that the absolute removal of all of the deflected threads is insured; said rotary thread removing means including a knife so mounted, shaped and arranged with respect to its coacting cutter plate and said cutter plate being so shaped that the cutting edge of the knife will be automatically sharpened by the operation of the machine and will at the same time permit the machine to be run at a very high rate of speed without injury to the fabric being operated upon.

A practical embodiment of the invention is represented in the accompanying drawings in which only so much of a machine of the above character is illustrated as will give a clear understanding of my invention.

Figure 1 represents the machine in front elevation. Fig. 2 is a view of the same in end elevation, partly in section, with the cover plate for the head also removed. Fig. 3 is a detail vertical section on an enlarged scale of the parts shown in section in Fig. 2. Fig. 4 is a detail section taken in the plane of the line A—A of Fig. 3. Fig. 5 is a detail section taken in the plane of the line

B—B of Fig. 3. Fig. 6 is a detail plan view of the cutter head. Fig. 7 is a top plan view of the knife. Fig. 8 is a detail horizontal section taken in the plane of the line C—C of Fig. 3. Fig. 9 is a detail horizontal view taken in the plane of the line D—D of Fig. 3. Fig. 10 is an inverted plan view of the cutter plate. Figs. 11 and 12 are detail front and edge views respectively of the lower end of the deflected blade, and Fig. 13 is a detail sectional view of the cutter plate on a greatly enlarged scale, with the path of the cutting edge of the knife indicated in connection therewith.

The machine table is denoted by 1, the upright by 2, the overhanging arm by 3, and the head by 4. The usual power driven horizontally disposed rotary shaft 5 is mounted in the machine frame, which shaft is operatively connected in the usual manner to the vertically reciprocating needle bar 6 and presser bar 7 within the head 4. The presser foot 8 coacts with the feed plate 9 of the fabric feeding mechanism, which mechanism may be of any well known or approved construction, and will not be specifically described herein.

A rotary cutter shaft 10 is horizontally disposed beneath the table 1, and the shaft is driven, in the present instance, at twice the rotary speed of the shaft 5, through a belt and pulley connection 11, 12, 13. This cutter shaft 10 is provided with a head 14, having an inclined seat 15 for the knife 16, which knife is secured to the head 14 by a suitable fastening screw 17 passing through an elongated slot 18 in the said knife. The head 14 is provided with a lip 19, forming a guide for one of the side edges of the knife. The knife 16 is provided with a diagonal cutting edge 20 beveled on its inner face to present a sharp edge. The relationship of the inclined seat 15 on the cutter head to the diagonal edge 20 of the knife is such that the entire cutting edge travels in a circular path concentric with the axis of the shaft 10, for obtaining a shearing cut with respect to the cutter plate to be immediately described.

The cutter plate is denoted by 21, and it is secured in the proper position on the table 1 with respect to the rotary cutter, by suitable fastening screws 22. This plate has a transversely elongated hole 23, therethrough in position to receive the lower end of the deflector blade to be hereinafter described.

The under surface of the cutter plate 21 is cut away in the plane of the rotary cutter in such a manner that the cutting edge 20 of the knife 16 first comes into engagement 5 with the cutter plate as the edge reaches the hole 23 and leaves its engagement with the cutter plate as the edge passes by the said hole. A slight ridge 24 is formed in the undersurface of the plate 21, adjacent 10 to the hole 23, which ridge projects into the circular path of the cutting edge 20 of the knife 16, so that the said edge is slightly deflected for a very short portion of its rotary movement at the hole 23, thereby causing 15 the edge to be self-sharpening and maintaining the edge at a high degree of cutting efficiency. The cutaway surfaces 25, 26, to the front and rear of the ridge 24, are so arranged that the cutting edge 20 has a free 20 movement up to the hole 23, and a free movement after it leaves the ridge 24, this latter free movement serving also to insure the free removal of the deflected threads separated from the fabric by the knife. 25 The thread deflecting blade is denoted by 27, and its lower end is flattened transversely of the line of feed of the machine. The blade has a diagonal bottom straight edge 28 for facilitating the entry of the blade 30 between the crosswise threads of the fabric. This diagonal straight edge 28 has a notch 29 near its upper end, which notch serves to invariably engage the same longitudinal thread of the fabric, thus insuring the 35 proper number of longitudinal threads being deflected by the blade. This blade is attached to the vertically reciprocating needle bar 6, and its bottom edge passes through a transverse hole 30, in the presser foot 8, and 40 through the transverse hole 23 in the cutter plate 21.

The movements of the cutter with respect to the deflecting blade are so timed that the deflecting blade forces the required number 45 of longitudinal threads downwardly through the hole 23 and the blade is then withdrawn before the said deflected threads are acted upon by the knife 16 of the rotary cutter in its first revolution. The knife of the rotary 50 cutter is again caused to engage said deflected threads during its second revolution for absolutely insuring the removal of any of the deflected threads which might not be cleanly removed by the knife in its first 55 revolution. After this second revolution, the blade 27 again forces the threads beyond the next succeeding transverse thread or threads downwardly through the hole 23, it being understood that the fabric is moved 60 step by step rearwardly by the feeding mechanism.

It is also to be understood that the number of threads to be removed is controlled by the width of the blade 27, the knife of 65 the rotary cutter being of such width as to

cut any desired number of threads within reasonable limits.

A machine having its working parts constructed, arranged and operated as herein shown and described, will accurately operate upon the fabric being treated, to deflect only the desired number of longitudinal threads without injuring the transverse threads and will also insure the absolute and clean removal of the said deflected threads. The 70 machine will also be capable of a very rapid movement and will require very little attention, especially because of the form of the under surface of the cutter plate and the form and arrangement of the cutter knife, which insures the clean removal of the deflected threads and the self-sharpening of the cutting edge of the knife because of its coaction with the cutter plate. 75 80

By causing the knife to travel at a higher 85 rate of speed than the blade, a better cutting action of the knife is obtained upon the deflected threads every revolution of the knife.

It is evident that various changes might be resorted to in the construction, form and arrangement of the various parts without departing from the spirit and scope of my invention; hence I do not wish to limit myself strictly to the form herein shown and described. 90 95

What I claim is:

1. In a machine of the character described, thread deflecting means, and means rotating continuously in one direction during the operation of the machine, for cutting off the deflected threads, arranged to act more than once for each action of the thread deflecting means, said deflecting means serving to deflect the threads into the path of said cutting means. 100 105

2. In a machine of the character described, thread deflecting means, and means rotating continuously in one direction during the operation of the machine, for cutting off the deflected threads, arranged to act twice for each action of the thread deflecting means, said deflecting means serving to deflect the threads into the path of said cutting means. 110

3. In a machine of the character described, a reciprocating thread deflector and a rotary cutter for cutting off the deflected threads, said cutter being operable to act more than once on the deflected threads for each action of the thread deflector. 115

4. In a machine of the character described, a reciprocating thread deflector and a rotary cutter for cutting off the deflected threads, said cutter being operable to act twice on the deflected threads for each action of the thread deflector. 120 125

5. In a machine of the character described, a thread deflecting blade and a rotary cutter for cutting off the deflected threads, said cutter being operable to act 130

more than once on the deflected threads for each action of the blade.

6. In a machine of the character described, a reciprocating thread deflecting blade and a rotary cutter for cutting off the deflected threads, said cutter being arranged to act twice on the deflected threads for each action of the blade.

7. In a machine of the character described, a cutter plate having a hole therethrough, means for forcing the threads to be removed through said hole, and a knife rotating continuously in one direction during the operation of the machine, coacting with the plate to remove the deflected threads, the under side of said plate being shaped to keep the cutting edge of the knife sharpened.

8. In a machine of the character described, a cutter plate having a hole therethrough, means for forcing the threads to be removed through said hole, and a knife rotating continuously in one direction during the operation of the machine, coacting with the plate to remove the deflected threads, the under side of said plate being cut away to form a transverse ridge extending slightly into the path of the cutting edge of the knife for keeping the same sharpened.

9. In a machine of the character described, a cutter plate having a hole therethrough, means for forcing the threads to be removed through said hole, a rotary shaft, a cutter head thereon, and a knife seated on said head at an angle to the axis of the shaft, said knife having a diagonal cutting edge arranged to coact with the cutter plate to remove the deflected threads.

10. In a machine of the character described, a cutter plate having a hole therethrough, means for forcing the threads to be removed through said hole, a rotary shaft, a cutter head thereon and a knife seated on said head at an angle to the axis of the shaft, said knife having a diagonal cutting edge arranged to coact with the cutter plate to remove the deflected threads, the under side of the cutter plate being cut away to form a transverse ridge adjacent to the hole therethrough.

In testimony, that I claim the foregoing as my invention, I have signed my name in presence of two witnesses, this third day of September 1913.

JOHN W. ESHELMAN.
